UNITED STATES PATENT OFFICE.

RICHARD F. STEWART, OF BRIARCLIFF MANOR, NEW YORK.

BUTTER-PRINT-FORMING MACHINE.

1,425,711.

Specification of Letters Patent. Patented Aug. 15, 1922.

Application filed September 25, 1918. Serial No. 255,608.

To all whom it may concern:

Be it known that I, RICHARD F. STEWART, a citizen of the United States, residing at Briarcliff Manor, in the county of Westchester and State of New York, have invented new and useful Improvements in Butter-Print-Forming Machines, of which the following is a specification.

This invention relates to machines for forming moldable material into blocks or prints, and while it is particularly designed for forming blocks or prints of butter, and will be so described, it will be understood that it may be used with any moldable material.

It has for its object to provide means, automatic in operation, for severing blocks successively from a mass of butter fed to it; forming said successively severed blocks together and advancing them in the form of a continuous bar; shaping, solidifying, and, if desired splitting longitudinally, such bar; and finally, as herein shown, by manually operated means, cutting off the end of the shaped and solidified bar to form a print, or if the bar be split a plurality of prints; means being provided for regulating the standardizing of the size of such prints, and, furthermore, for impressing any desired mark or device thereon.

These results are accomplished by providing a receiving box to which the butter is fed; arranging a severing device in said box so that it will sever a block at regular intervals from the mass; so disposing a block advancing instrumentality as that it will force the blocks severed from the mass end to end through the box, shaping them and forming them into a continuous, solid bar; providing means for spreading said bar into a plurality of bars; and at the delivery end of the machine mounting a print cutting-off and stamping element which will be actuated to cut from the bar, prints of a regulated and standard size.

In the drawings herewith I have illustrated one embodiment of my invention, but it will be understood that the disclosure is illustrative and in no sense restrictive of my invention, as mechanical variations in structure may be made without departing from the invention herein set forth and claimed.

In said drawings:—
55 Figure 1 is a view in side elevation of my machine.

Figure 2 is a plan view, partly in section, of a clutch for controlling the operation of the print carrier-belt.

Figure 3 is an end view of the clutch 60 casing and a clutch member.

Figure 4 is a plan view of the machine with the hopper for the butter removed.

Figure 5 is a view in transverse section on line 5—5, Figure 4, looking in the direction of the arrow, the clutch being shown in section.

Figure 6 is a transverse section on line 6—6 of Figure 4.

Figure 7 is a longitudinal section of the 70 machine on a somewhat enlarged scale, showing the print cut-off and stamping mechanisms in down position.

Figures 8, 9 and 10 are detail views of a slightly different type of shaping box and 75 delivery throat.

In the drawings, 10 indicates the frame of the machine, which may be constructed of angle iron, or any suitable material, and supported upon suitable supports, such as 80 legs 12. The machine may be driven manually, or by power, a power-driven machine being here shown, the power being furnished by a motor, as 13, coupled with a worm shaft 14, which engages a worm wheel 15 mounted 85 on a crank shaft 16, which crank shaft is the main driving element of the mechanism.

The crank shaft, as shown in Figures 1, 4 and 7, is mounted transversely of the machine, near one end thereof, in suitable 90 bearings, and its crank arm 17, provided with an anti-friction roll, engages a slotted cross head 18 secured to a plunger rod 19 mounted in cross bars 20 and 21 arranged transversely of the machine, so as to reciprocate freely therein, the said plunger rod 95 being provided at its forward end with a head 22 from which extends rearwardly a top web or plate 23 and side wings or plates 24.

The said plunger reciprocates in a mold 100 box or casing 25, which box, as shown in Figure 7, is provided in one of its walls, the upper wall as here shown, with a feed opening, which feed opening in the present embodiment comprises a chute 26 communicating with a butter board or pan 27 into which the butter, or other material, is dumped and fed forward by a manual operation to the feed opening and into the 105 mold box 25.

As the crank shaft 16 is rotated, it will, through its crank 17, cross-head 18 and

plunger rod 19, reciprocate the plunger 22 forward and backward beneath the feed opening and force forward through the mold box the butter which feeds downwardly into said mold box 25, so that successive blocks or masses of butter will be periodically forced forward through the mold box. The web or apron 23 with which the plunger 22 is provided will, when the 10 plunger moves forward, serve as a cut-off plate to prevent the butter working downwardly behind the plunger, said apron 23 being of such length and width as to completely close the feed opening when the 15 plunger is in its forward position, as shown in Figure 7.

In order that the butter coming from the hopper 27, through the chute 26, may be cleanly severed from the mass in the form 20 of a block and not dragged forward or pushed off by the plunger, I provide severing means to cut off the butter which is fed downwardly into the box, in advance of the compressing and advancing action of 25 the plunger. This severing means comprises the broad knife plate 28 mounted so as to slide just above and upon the apron 23 of the plunger, said knife being of such 30 dimensions as to close the feed opening, and 35 having at its forward end a sharp severing edge. The said knife is mounted upon a cross block 29 to which is secured rods 30, two being shown in the present instance, which extend rearwardly and at their outer 40 ends slide in bearings 31 on the cross head 21 heretofore referred to. The rods 30 have spiral springs 32, which are compressed between the cross head 21 and the knife 29, and furnish the driving power for effecting 45 the cutting stroke of the knife. The said knife is coupled for movement rearwardly with the cross head 18 heretofore referred to by means of a spring latch 33 (see Figure 7) which engages the upper end of the 50 cross head, as shown, in such manner as that, when the cross head and plunger are moved rearwardly, the knife will be drawn back and the springs 32 put under compression, the said plunger and the knife 55 moving back together. When the cross head reaches its rearmost position, as shown in dotted lines in Figure 7, the spring latch 33 will strike with its rear end a tripping 60 projection 34, which will disengage the latch from the cross head, as shown in dotted lines in Figure 7, and the springs 32 will then shoot the knife forward to the full line position in said figure, cutting off the butter which has fed down from the hopper into 65 the feed box in the form of a block, and closing the feed opening leading from the hopper to the box. It will be seen that this severing device operates when the plunger has been retracted to its rearmost position 70 and after the severing action the plunger

22 moves forward, forcing the severed block through the mold box.

As the successive blocks are forced forward, they will, of course, smear together and form a continuous bar of butter, which 70 will be forced forwardly to a shaping box or throat 35 at the forward end of the mold box, and preferably this shaping box will have its upper wall inclined, as shown at 75 36, and its side walls will also be tapered, as shown in dotted lines at 37, in Figure 4, a removable cover 38 being provided for said shaping box. The said box 35 will serve to shape and slightly compress the butter coming from the mold box, and this 80 box may be made so as to divide the bar vertically and longitudinally into a plurality of bars, a box capable of forming two bars being shown in the present embodiment. This is accomplished by means 85 of a central partition 39, the rear end of which is chamfered off or tapered, as at 40, in order to split and aid in shaping and solidifying the butter passing through the 90 shaping box or throat.

As the bar or bars of butter issue from the shaping throat or box, they are delivered to a carrier apron 41 mounted, as shown, upon suitable rollers 42 carried upon an extension frame 43 of the machine, and in 95 order that the bar or bars may be cut into prints of proper size and have stamped thereon any appropriate design or trade device, I provide a cutting-off and stamping device comprising a severing or cutting element 43', here shown as a cross wire, mounted in depending arms 44 of a cross bar 45, carried by swinging arms 46 which extend rearwardly and are supported in bearings 47 in the cross bar 21 in which, as shown 100 in Figures 1 and 2, they are free to rock and slide, stop pins 48 being provided at the rear end of said arms 46 so as to prevent their accidental withdrawal from their 105 bearings. The said arms 46 are spring-supported by spring plungers 49, one for each of said arms, mounted in slotted barrels 50 fixed to the machine frame, the said spring plungers tending always to hold the bars 46 and the print cutting-off devices elevated, 110 as shown in Figure 1.

Supported between said bars 46 is a print block 52, the said print block being arranged in advance of the print cut-off mechanism, and being made with a removable printing face or block 52 detachably secured by thumb screws 53, so that the printing surface may be readily changed to suit the design or mark of a particular user. A handle 54 is provided by means of which the cut-off and print block may be forced downwardly to cut a print from the ribbon and mark it.

In order that the prints may be regulated as to size, I provide a stop and regulating 130

bar 55 which is adjustably mounted on arms 56 pivotally connected at their rear ends to the bracket arms 44. The said regulating plate 55 lies normally in the position shown 5 in Figure 1, and as the butter bar feeds forward in the direction of the arrows, it will strike the bar 55, which will indicate to the operator that the bar has been obtruded from the shaping box a sufficient distance to 10 give a print of the required size, whereupon he will manually force the print severing mechanism downwardly and cut off a print from the end of the butter bar, at the same time marking said print, all as shown in 15 Figure 7. In order that the plate 55 will be lifted out of the path of the severed print, it is provided with a hanger 57 having an engaging loop or projection 58 at its extreme upper end and which serves to hold it, 20 as shown in Figure 1, in the path of the butter bar prior to cutting off of the print. When the downward thrust of the cutter is made, and it is brought to the position shown in Figure 7, the print block head will 25 engage an offset or shoulder 59 formed on the hanger 57, which hanger is of spring material, so that the shoulder 59 will snap over the end of the print block, and as the springs 49 raise the bars 46 and the cutting 30 instrumentalities to their normal position, the regulator bar 55 will be carried upwardly clear of the path of travel of the severed prints. After the carrier belt 41 has moved 35 the print clear, as, for example, to the position shown in dotted lines in Figure 1, the operator will simply knock off the hanger 57 so as to disengage the shoulder 59 and permit the stop and regulator bar to fall to the 40 position shown in Figure 1, upheld by the end hook or offset 58.

The carrier belt 41 is driven by a sprocket wheel 60, mounted on the shaft of the rear roller, said sprocket wheel 60 being connected by sprocket chain 61 with a driving 45 sprocket 62 on the crank shaft 16 of the machine, the forward end of the carrier belt 41 being mounted upon a roller 63 carried in spring bearings (see dotted lines) 64 with an adjusting device 65, by means of which the 50 spring plates 66, which form the spring bearings for the roller 63, may be adjusted to properly tension the carrier belt.

It is obvious that the travel of the carrier belt must be suspended for the cutting off 55 and printing of the block. Otherwise the cut would be on an incline and the print would be smeared, which would result in an imperfect print of butter. In order to intermittently suspend the travel of the belt 60 41, when the print cutting and stamping mechanism heretofore described is operated, I provide a clutch mechanism between the sprocket 60 and the shaft 67 of the drive roller 42, which is actuated whenever the 65 print cutting mechanism is operated, to dis-

connect the sprocket wheel, which is continuously driven by the crank shaft, from the roller shaft. This clutch mechanism is shown in Figures 2, 3 and 5, and comprises a housing 68 secured in any suitable manner, as by screws 69, to the frame of the machine. The said housing is provided with a cam slot 70, as shown in Figure 2, through which slot projects an operating arm 71 engaging a ring 72, which ring 72 has radially-disposed inwardly projecting pins 73 which engage a circumferential groove in a clutch member 74 slidably mounted on the shaft 67 but keyed thereto so as to rotate therewith. The said clutch member 74 has a ratchet face 75 opposed to a ratchet face 76 on the sprocket wheel 60, which rotates freely on the shaft 67 when in the idle position shown in Figure 2. Upon angular movement of the arm 71, the ratchet member 74 will be 80 moved by the action of the cam slot 70 into and out of engagement with the ratchet on the sprocket wheel 60, so as to effect a driving engagement or a release of the shaft 67 and a consequent driving or stopping of the 85 roller 42 and carrier belt 41.

The said radially-disposed clutch operating arm 71 is connected with one of the cut-off and print supporting side bars 46 by means of a connection 77, as clearly shown 90 in Figures 1, 4 and 5, in such a manner as that on the downward movement of the cut-off and print block from the position shown in Figure 1 to the position shown in Figure 7, angular movement to unship the clutch 100 will be imparted to the radial arms 71, releasing the shaft 67 and its roller 42 from the continuously rotating sprocket 60, thus stopping the carrier belt 41 with the end of the butter bar in position to be cut off and 105 printed.

It will be noted that this unshipping of the clutch and stoppage of the travel of the carrier belt takes place when the bar-forming plunger is in retracted and inactive position, so that when the carrier belt is stopped for the cut-off of a print, there is no feeding forward of the butter bar along the carrier belt. In other words, the butter bar will feed forward, under the influence of 110 the plunger, a sufficient distance to obtrude the proper length of print, and will then be retracted for a new thrust and during that retraction the operator will manually actuate the cut-off and stamp to sever the print, 115 such actuation, as has been stated, causing stoppage of the carrier belt. Immediately the cut off and stamping mechanism is released, it will be automatically raised by the spring supports 49, the clutch mechanism will automatically couple the roll and its driving sprocket, and the carrier belt 120 resume its travel, taking the print forward to any suitable delivery point.

The pivoted and sliding mounting of the 130

side bars 46 in the bearings 47 of the cross-bar 21, permits, not only the up and down swinging movement of the print-cutter and stamp, but also allows a bodily movement 5 of these elements forward or backward, if necessary, in their manual operation to accommodate their movements to varying positions of the prints and prevent smearing in event of contact of cutter and print 10 block with the butter prior to clutch release and stoppage of the carrier belt.

In that form of the invention shown in Figures 8, 9 and 10, I have illustrated a different form of shaping box or throat 15 designed particularly for filling cans with round prints of butter. In this adaptation of the machine, there will be no change in the mechanism for severing the butter from the mass or forcing it forward through the 20 mold box and throat, but the throat will be so adapted as to shape the rectangular-ended butter bar to circumferential form and deliver it to a round can. At the front of the shaping box is placed an insert 78, 25 which forms the shaping throat having a round orifice 79 therein with walls 80 sloping forwardly to the opening and arranged about the sloping walls at regular intervals are a series of projections 81, the present 30 example showing these as four in number and arranged ninety degrees apart. Where the butter bar is of rectangular shape, these projections 81 will be so disposed as to catch the corners of the square bar, as illustrated 35 in Figure 9, and their action will be to split the corners of the square bar and spread the surplus butter along their sloping walls and gradually shape it to the round contour of the discharge opening. The bar thus shaped 40 and rounded passes to a circumferential throat 82 on the projecting end of which the can 83 to be filled is slipped. As the advancing butter bar pushes the can from the throat 82, the bar will be severed close to 45 the top of the can in any suitable manner, either by a hand severing device or by so adapting the cut-off mechanism shown in Figure 7 to this type of machine as that it can be forced downwardly to sever the butter bar immediately the can leaves its supporting throat under the action of the advancing bar of butter.

I claim:

1. In a machine of the class described, 55 the combination of a block-forming box having an inlet, a block-severing device movable past said inlet, a block advancing instrumentality movable past said inlet means to effect a simultaneous retraction of said severing and advancing means, means for giving an independent forward thrust to said severing means, means for forming the blocks into a bar as they are advanced, a cut-off device to sever a print from the bar, 60 means for limiting the forward movement 65

of said bar, a carrier to which the print is delivered and a clutch device operable on movement of said cut-off to stop and start said carrier.

2. In a machine of the class described, the combination of a block-forming box having an inlet, a block-severing device movable past said inlet, a block-advancing instrumentality movable past said inlet, means for actuating said advancing instrumentality, 70 means for giving a forward thrust to said severing device prior to each operative movement of said advancing instrumentality, and a connection between said advancing instrumentality and said severing device 75 to retract the latter on rearward movement of said advancing instrumentality.

3. In a machine of the class described, the combination of a block-forming box having an inlet, a block-severing device movable 80 past said inlet, a block-advancing instrumentality movable past said inlet, means for actuating said block-advancing instrumentality, means for giving a forward 85 thrust to said severing device prior to each operative movement of said advancing instrumentality, a connection between said advancing instrumentality and said severing device to retract the latter on rearward movement of said advancing instrumentality, 90 and means for releasing said severing device at a pre-determined point in the rearward travel of said advancing instrumentality.

4. In a machine of the class described, the combination of a block-forming box having an inlet, a block-severing and cut-off blade to sever a block and close said inlet, a plunger having a cut-off apron to advance a block and close said inlet, means reciprocating said plunger, and means for actuating said blade in advance of the forward movement of said plunger.

5. In a machine of the class described, the combination of a block-forming box having 110 an inlet, a block-severing and cut-off blade to sever a block and close said inlet, a plunger having a cut-off apron to advance a block and close said inlet, means reciprocating said plunger, means for actuating said blade in advance of the forward movement of said plunger, and means to couple 115 said blade and plunger for simultaneous retraction.

6. In a machine of the class described, the combination of a block-forming box having an inlet, a block-severing and cut-off blade to sever a block and close said inlet, a plunger having a cut-off apron to advance a block and close said inlet, means for reciprocating said plunger, means for actuating said blade in advance of the forward movement of said plunger, means to couple 125 said blade and plunger for simultaneous retraction, and means for automatically re- 130

leasing said blade at a predetermined point in its rearward movement.

7. In a machine of the class described, the combination of a block-forming box having an inlet, a cut-off blade adapted to sever a block and close said inlet, a plunger having a cut-off apron adapted to advance the block and close said inlet, means for reciprocating said plunger, means for giving a forward thrust to said blade, a latch to couple said plunger and blade for simultaneous retraction, and means for tripping said latch at a predetermined point in the rearward movement of said blade.

15 8. In a machine of the class described, the combination of a block-forming box having an inlet, a cut-off blade adapted to sever a block and close said inlet, a plunger having a cut-off apron adapted to advance the block and close said inlet, means for reciprocating said plunger, spring means for giving a forward thrust to said blade, a latch to couple said plunger and blade for simultaneous retraction, and means for tripping said latch 25 at a predetermined point in the rearward movement of said blade.

9. In a machine of the class described, the combination of a block-forming box having an inlet, a block-severing device movable past said inlet, a block-advancing instrumentality movable past said inlet, spring means for giving a forward thrust to said severing device, a reciprocating cross-head to actuate said advancing instrumentality, a 35 spring latch on said severing device to engage said cross-head for simultaneous retraction of said severing device and advancing instrumentalities, and means to trip said spring latch and release said spring-operated 40 severing device at a predetermined point in its retraction.

10. In a machine of the class described, the combination of a block-forming box having an inlet, a block-severing blade movable past said inlet, a block-advancing plunger movable past said inlet, a continuously driven carrier belt to receive material advanced by said plunger, a print cut-off to sever said material, and clutch mechanism 50 operable on movement of said cut-off to stop said carrier belt.

11. In a machine of the class described, the combination of a block-forming box having an inlet, a block-severing blade movable past said inlet, a block-advancing plunger movable past said inlet, a continuously driven carrier belt to receive material advanced by said plunger, a rising and falling print-cutting device, and clutch mechanism 55 operable on downward movement of the cut-off device to stop said carrier belt and to start said carrier on return movement of said cut-off device.

12. In a machine of the class described, 60 the combination of block-severing means,

block-advancing means, means for forming a plurality of the blocks into a bar, means for limiting movement of said bar after a predetermined extrusion thereof, means for cutting a print from said bar extruded, an 70 automatically engageable connection between said cutting means and said limiting means to move the latter from the path of the print on withdrawal of said cutting means.

13. In a machine of the class described, the combination of block-severing means, block-advancing means, bar-forming means comprising a throat through which the blocks are forced by said advancing means, a movable stop device in the path of the bar, a movable cutter to sever a print from the bar, and a latch on said stop to engage said cutter and lift said stop from the path of the print on withdrawal of said cutter.

14. In a machine of the class described, the combination of block-severing means, block-advancing means, bar-forming means comprising a throat through which the blocks are forced by said advancing means, a 90 swinging cutter to sever a print from the bar, means for holding said cutter normally raised, a stop device in the path of the bar, and a spring latch to automatically couple said cutter and stop on the cutting thrust 95 of the cutter and lift said stop from the path of the print on withdrawal of said cutter.

15. In a machine of the class described, the combination with bar-forming and advancing instrumentalities of means for severing a print from the bar, comprising a swinging frame having a bar cutter, spring supports to hold said frame normally lifted, a pivotally mounted stop in the path of said bar 105 and means to automatically couple said cutter and stop on the cutting thrust of said cutter to lift said stop from the path of the bar on return movement of said cutter.

16. A print cut-off for machines of the 110 class described, comprising a swinging and longitudinally movable frame, a cutter depending from said frame, a stop device pivotally mounted on said frame, and a removable print block on said frame between 115 said cut-off and said stop device.

17. A print cut-off for machines of the 120 class described, comprising a swinging and longitudinally movable frame, a cutter depending from said frame, a stop device having an inclined face pivotally mounted on said frame, and a removable print block on said frame between said cut-off and said stop device.

18. A print cut-off for machines of the 125 class described, comprising a swinging and longitudinally movable frame, a cutter depending from said frame, a longitudinally adjustable stop device having an inclined face pivotally mounted on said frame, and 130

- a removable print block on said frame between said cut-off and said stop device.
19. A print cut-off for machines of the class described, comprising a swinging and longitudinally movable frame, a cutter depending from said frame, a longitudinally adjustable stop device having an inclined face pivotally mounted on said frame, a removable print block on said frame between 5 said cut-off and said stop device, and a spring-latch coupling said stop-device and said cutter and shiftable to maintain the parts in relatively different positions.
20. In a machine of the class described, the combination with a cut-off device to sever a print from a bar, a traveling carrier to which said print is delivered, a driving shaft for said carrier, a freely rotating clutch member on said shaft, a sliding clutch member splined to said shaft, a shifting collar connected with said sliding clutch member, and a connection between said collar and said cut-off device to couple and uncouple said clutch members on opposite 10 movements of said cut-off device.
21. In a machine of the class described, the combination with a cut-off device to sever a print from a bar, a continuously driven carrier to receive the print, a rotary shaft 15 to drive said carrier, a continuously driven clutch member on said shaft, a sliding clutch member splined to said shaft, a clutch shifting collar connected to said sliding clutch member, a clutch containing box having 20 a cam slot therein, a rotary arm projecting through said slot and connected with said collar, and a connection between said arm and said cut-off device to couple and uncouple said clutch when the cut-off device 25 is moved in opposite directions.
22. In a machine of the class described, the combination with a cut-off device to sever a print from a bar, a traveling carrier to which the print is delivered, a rotating shaft 30 to drive said carrier, a continuously driven clutch member freely rotatable on said shaft, a sliding clutch member splined to said shaft, a clutch shifting collar connected with said sliding clutch member, a clutch 35 receiving box having a cam slot in its wall,
- a collar shifting arm projecting radially through said slot, and a connection between said arm and said cut-off device to couple and uncouple said clutch when said cut-off is moved in opposite directions.
23. A mold box for machines of the class described, rectangular in cross-section, and a throat circular in cross-section to which 40 said box delivers.
24. A mold-box for machines of the class described, having a throat of different shape in cross-section from that of the mold-box, and means to uniformly displace the material as it passes from said box to said throat and feed it properly to said throat.
25. A mold-box for machines of the class described, having a throat the wall of which is curved, and means to upset and spread the material laterally as it passes from said box to said throat and feed it properly to 45 said throat.
26. A mold-box for machines of the class described, rectangular in cross-section, and having a throat circular in cross-section, and projections extending into the path of the material to engage the material passing through the box and spread it laterally as it passes to said throat.
27. A mold box for machines of the class described, rectangular in cross-section, having 50 a throat circular in cross-section, and cutting projections between said box and throat to engage the corners of the material and spread it laterally as it passes from said box to said throat.
28. A mold-box for machines of the class described, rectangular in cross-section, and having a throat circular in cross-section to which the walls of said box gradually slope, and cutting projections at the corners of 55 said box between said box and throat to divide the corners of and spread the material laterally as it passes to said throat.
- In testimony whereof I hereunto set my hand in presence of two subscribing witnesses.
- RICHARD F. STEWART.
